(57) **CLAIM**

The ornamental design for a knife, as shown and described.

DESCRIPTION

FIG. 1 is a top, front, right side perspective of a first embodiment of a knife;

FIG. 2 is a right side elevation view of the first embodiment;

FIG. 3 is a left side elevation view of the first embodiment;

FIG. 4 is a rear elevation view of the first embodiment;

FIG. 5 is a front elevation view of the first embodiment;

FIG. 6 is a top plan view of the first embodiment;

FIG. 7 is a bottom plan view of the first embodiment;

FIG. 8 is a top, front, right side perspective of a second embodiment of a knife;

FIG. 9 is a right side elevation view of the second embodiment;

FIG. 10 is a left side elevation view of the second embodiment;

FIG. 11 is a rear elevation view of the second embodiment;

FIG. 12 is a front elevation view of the second embodiment;

FIG. 13 is a top plan view of the second embodiment; and,

FIG. 14 is a bottom plan view of the second embodiment.

The broken lines that appear on the drawings form no part of the claimed design and are included for illustrative purposes only.
